RECLINING ARTICLE OF FURNITURE

Anton Lorenz, Buffalo, N. Y., and Johannes Luckhardt, Berlin-Dahlem, Germany; said Luckhardt assignor to said Lorenz

Application May 26, 1949, Serial No. 95,412

22 Claims. (Cl. 155—105)

1

This invention relates to articles of furniture, and more particularly to a reclining article of furniture.

An object of the present invention is to provide a reclining article of furniture wherein the seat and back-rest constituting movable links of a constrained complex linkage may be readily tilted from a sitting position into a reclined position.

Another object of the present invention is to provide a reclining article of furniture wherein the seat and back-rest constitute movable links of a constrained complex linkage and wherein a leg-rest swingably mounted on the seat may be propelled to a great extent during the initial tilting of the back-rest and the seat from the sitting position into a reclined position.

A further object of the present invention is to improve on the art of reclining articles of furniture as now ordinarily made.

With the above and other objects of the invention in view, the invention consists in the novel construction, arrangement and combination of various elements and parts, as described hereinafter and set forth in the claims hereof, certain embodiments of the same being described in the specification and being illustrated in the accompanying drawings forming part of this specification, wherein:

Fig. 1 is a side elevational view of a tiltable office chair,

Fig. 2 is a sectional view taken on line 2—2 of Fig. 1,

Fig. 3 is a side elevational view of a tiltable chair,

Fig. 4 is a side elevational view of an arm chair, a portion of a side wall of the frame being broken away,

Fig. 5 is a fragmentary view taken on line 5—5 of Fig. 4,

Fig. 6 is a sectional view taken on line 6—6 of Fig. 4,

Fig. 7 is a sectional view taken on line 7—7 of Fig. 4,

Fig. 8 is a simplified diagrammatical illustration of the link-systems of the arm chair shown in Fig. 4,

Fig. 9 is a side elevational view of another embodiment of an office chair,

Fig. 10 is a sectional view taken on line 10—10 of Fig. 9,

Fig. 11 is a side elevational view of a further embodiment of an office chair,

Fig. 12 is a side elevational view of an arm chair, a portion of a side wall being broken away, and

2

Fig. 13 is a sectional view taken on line 13—13 of Fig. 12.

Referring now to Figs. 1 and 2, 20 generally indicates a support of the office chair, said support being in the shape of a customary pedestal.

The rear end portion of a seat 22 is pivoted at 24 to a back-rest 26, a portion of which extends below the plane of said seat. On each side of the office chair, the rear end portion of a lower connecting link 28 arranged below the plane of the seat 22 is pivoted to the downwardly extending portion of the back-rest 26 at 30. Each of said lower connecting links 28 is pivoted at 32 to an adjustable bracket 34 of the pedestal or support 20. The front end portion of each lower connecting link 28 is pivoted at 36 to one end of a front connecting link 38, the other end of which is pivoted at 40 to the front end portion of the seat 22. On each side of the chair, one end of a guiding link 42 is pivoted to the bracket 34 of the support 20 at 44. The other end of said guiding link 42 is pivoted to the back-rest 26 at 24 in coaxial alignment with the pivotal connection between the back-rest 26 and the seat 22. Thus, the office chair comprises a constrained complex linkage having a plurality of movable links and a stationary link. A portion of the support between the pivots 32 and 44 is included in said constrained complex linkage as said stationary link. The movable links of the constrained complex linkage include the seat 22, the back-rest 26, the lower connecting link 28 and the front connecting link 38.

The sitting position of the movable links of the constrained complex linkage shown in full lines is limited by stops 46 arranged on forward extensions of the bracket 34 for abutting engagement with the seat 22. Compression springs 48 arranged between said forward extensions of the bracket 34 and the lower connecting links 28 act as a load on said lower connecting links and tend to urge the movable links of the constrained complex linkage into the sitting position.

When the user of the chair presses against the back-rest 26, the movable links of the constrained complex linkage may be brought against the action of the springs 48 from the full line sitting position into a reclined position, for example into the reclined position shown in dash and dot lines, whereby the back-rest 26 and the seat 22 are tilted to a certain extent. The movable members of the chair may be returned into the sitting position by shifting the weight of the person resting on the chair forwardly; the compression springs 48 assist in the returning of the movable members of the chair into the sitting position.

On each side of the chair, the rear end portion of an arm-rest 50 is pivoted to the back-rest 26 at 52. The front end portion of the arm-rest 50 is pivotally connected at 54 with the upper portion of a bar 56, the lower portion of which is pivoted to the seat 22 at 58.

According to the embodiment of a chair shown in Fig. 3, the chair comprises a seat 122 pivoted to the back-rest 126 at 124 and pivoted to the front connecting link 138 at 140. The front connecting link 138 is pivoted at 136 to the lower connecting link 128, the rear end portion of which is pivoted at 130 to a downward extension of the back-rest 126. Said lower connecting link 128 is pivoted to the support 120 at 136 in coaxial alignment with its pivotal connection with the front connecting link 138. A bell-crank lever 160 is swingably mounted on the support 120 at 144. The arm 142 of said bell-crank lever 160 acting as a guiding link is pivoted to the seat 122 at 125. The other arm 162 of said bell-crank lever 160 is connected with one end of a tension spring 164, the other end of which is fixed to a stationary point of the support 120.

Thus, the chair shown in Fig. 3 comprises again a constrained complex linkage. The guiding link 142, however, is pivoted to the seat 122 at 125 at a point spaced from the pivotal connection 124 between the back-rest 126 and the seat 122.

When the back-rest 126 is tilted from its sitting position into a reclined position, for example the reclined position shown in dash and dot lines, the remaining movable links of the constrained complex linkage are brought into the dash and dot line position, whereby the seat 122 is tilted in dependence on the tilting of the back-rest 126.

The spring 164 has the tendency to return the movable links of the constrained complex linkage into the sitting position.

The sitting position is limited by an abutment of the lower connecting link 128 against a stop 146 arranged on the support, and the extreme reclined position of the movable links of the constrained complex linkage is limited by an abutment of said lower connecting link 128 against a stop 150 arranged on the support 120.

According to the embodiment shown in Figs. 4-8, the support 220 comprises connected side frames 219 and 221, the upper portions of which constitute the arm rests of the arm-chair.

On each side of the chair, the rear end portion of the seat 222 is pivoted at 224 to lugs 227 rigidly connected with the back-rest 226. Lower extensions 229 of the back-rest, in rigid connection with the latter, extend downwardly on each side of the chair and are pivoted at 230 to rear end portions of lower connecting links 228. Each lower connecting link 228 is swingably mounted at 232 on a stud 266 (see Fig. 6) secured to the side frame of the support 220. The front end portion of each lower connecting link is pivoted at 236 to one end of a front connecting link 238, the other end of which is pivoted at 240 to the seat 222. An arm 242 of a bell-crank lever 268 swingably mounted on a transverse rod 244 of the support is rotatably connected with a transverse rod 223 connecting the downward extensions 229 of the back-rest 226 with each other. As may be gathered from Fig. 5, said bell-crank lever 268 is arranged in the center of the chair. The arm 242 of said bell-crank lever 268 acts as a guiding link.

A leg-rest 270 swingably mounted on the front

end of the seat 222 at 272 is pivotally connected at 274 with one end of a controlling link 276, the other end of which is pivoted at 278 to the arm 280 of the bell-crank lever 268. Said arm 280 constitutes a controlling element of the controlling mechanism connected with the leg-rest 270.

The sitting position (shown in full lines) of the movable members of the arm chair is limited by an abutment of the arm 280 of the bell-crank lever 268 against a transverse rod 246 of the support, which acts as a stop. The extreme reclined position (shown in dash and dot lines) of the movable members of the chair is limited by an abutment of said arm 280 of said bell-crank lever 268 against a stop 250. As best shown in Figs. 4 and 7, said stop is slideable in a slot 282 of the side frame 221. The stop 250 may be adjusted in a desired position by means of a crank 284 connected to said stop through the medium of bevel gears 286 and a shaft 288 screwed into the bore of a member 290 connected with one end of the stop 250.

The leg-rest 270 connected with the guiding link 242 through its controlling mechanism 280, 276 constitutes a load acting on the links of the constrained complex linkage for returning the movable members of the chair from a reclined position into the sitting position.

Fig. 8 illustrates in a somewhat simplified manner the constrained complex linkage of the armchair shown in Fig. 4. The link-system of the arm-chair includes the seat 222, the back-rest 226, the lower connecting link 228 and the front connecting link 238, said links being connected with each other at 224, 230, 236 and 240. The lower connecting link 228 is swingable about the stationary point 232. The guiding link 242 swingable about the stationary point 244 is pivoted to the back-rest 226 at 223 at a point spaced from the pivotal connection 224 between the back-rest 226 and the seat 222. The leg-rest 270 swingably mounted on the seat 222 at 272 is pivoted to the controlling link 276 at 274, said controlling link 276 being pivoted at 278 to the controlling element 280 rigidly connected with the guiding link 242.

According to the embodiment of an office chair shown in Figs. 9 and 10, a seat 322 is pivoted to a back-rest 326 at 324. On each side of the chair a lower extension of the back-rest 326 is pivoted at 330 to a lower connecting link 328 arranged below the plane of the seat 322 and swingably mounted at 332 on an adjustable bracket 334 of a pedestal or support 320. The front end of each lower connecting link 328 is pivoted at 336 to one end of a front connecting link 338, the other end of which is pivoted to the seat 322 at 340.

On each side of the chair a pin 392 projecting from the back-rest 326 is slidably engaged with a slot 394 of the bracket 334. Said pin 392 and slot 394 constitute cooperating guiding means slidably engaged with each other.

Above described link-system constitutes a constrained complex linkage. The sitting position of the movable links of said constrained complex linkage is limited by an abutment of the seat 322 against forwardly projecting arms of the bracket 334. A compression spring 348 arranged between said bracket 334 and the lower connecting link 328 tends to urge the movable links of the chair into the sitting position shown in full lines. When the user of the chair tilts the back-rest 326 backwardly into a reclined position, for example into the position shown in dash and dot lines, the

seat 322 forming, likewise, a movable link of the constrained complex linkage is also tilted into the position shown in dash and dot lines. The movable members of the chair may be returned from a reclined position into the sitting position when the occupant of the chair relieves the pressure on the back-rest and shifts his weight somewhat forwardly. The compression spring 348 acting as a load on the lower connecting link 328 assists in the returning of the movable members into the sitting position. The chair is provided at each of its sides with an arm-rest 350 pivoted to the back-rest 326 at 352 and pivoted to a bar 356 at 354. The bar 356 is swingably mounted on the seat 322 at 358.

According to the embodiment of an office chair shown in Fig. 11, again, the seat 422 is pivoted to the back-rest 426 at 424, the back-rest is pivoted at 430 to the lower connecting link 428, the latter is swingably mounted at 432 on the bracket 434 of the support 420 and the front connecting link 438 is pivoted at 436 to the lower connecting link 428 and at 440 to the seat 422. According to Fig. 11, however, the pivot 424 between the back-rest 426 and the seat 422 is also slidably engaged with a slot 494 of the bracket 434 of the support 420.

A compression spring 448 arranged between the bracket 434 and the lower connecting link 428 tends to urge the movable members of the chair into the sitting position limited by an abutment of the seat 422 against the forwardly extending arms of the bracket 434.

The rear end of an arm-rest 450 is pivoted at 452 to the back-rest 426. The front end of said arm-rest 450 is pivoted at 454 to a bar 456 pivoted at its other end to the seat 422 at 458.

The arm-chair shown in Figs. 12 and 13 has a support 520 comprising connected side frames 519 and 521. The back-rest 526 is pivoted at 524 to the rear portion of the seat 522 and at 530 to the rear portion of lower connecting links 528 swingably mounted on the support 520 at 532. The front end of each lower connecting link 528 is pivoted at 536 to one end of a front connecting link 538, the other end of which is pivoted to the seat 522 at 540.

As shown in Figs. 12 and 13, on each side of the chair, the seat 522 is provided with a pin 592 projecting from the side of the seat. Each pin is slidably engaged with a recess or slot 594 arranged on a side frame of the support 520.

The sitting position of the movable members of the chair is limited by a stop 546 arranged on the support for cooperation with the back-rest 526. The extreme reclined position of the movable members of the chair is limited by the rear wall 517 of the support against which the back-rest 526 may abut.

On each side of the chair one arm 581 of a controlling bell-crank lever 583 swingably mounted on the support 520 at 585 is in engagement with the back-rest 526. According to the embodiment shown in Fig. 12 said arm 581 carries a pin 587 slidably and rotatably engaged with a slot 589 of the back-rest. The other arm 580 of said controlling bell-crank lever 583 is pivoted at 578 to the rear end portion of a controlling link 576, the front end of which is pivoted at 574 to a leg-rest 570 swingably mounted on the seat 522 at 572.

When the back-rest 526 and seat 522 are brought from the sitting position shown in full lines into a reclined position shown in dash and dot lines, the leg-rest is propelled from the position shown in full lines into the position shown

in dash and dot lines by means of the controlling mechanism 583, 576 connected with the leg-rest and the back-rest. The slot 589 on the back-rest can be omitted and the arm 581 of the bell-crank lever 583 can be pivoted to the back-rest, if the slot 594 guiding the pin 592 of the seat 522 is of such a shape that a pivot connecting the back-rest 526 with the arm 581 of the controlling bell-crank lever is moved along a circular path, the center of which coincides with the axis of the pivot 585.

The controlling mechanism 583, 576 permits a swinging movement of the leg-rest 570 about its pivot 572 to a great extent, although the back-rest 526 may be tilted only slightly.

The leg-rest 570 connected to the back-rest 526 through its controlling mechanism 583, 576 acts as a load on the movable links of the constrained complex linkage of the chair and contributes to a return movement of said movable links from a reclined position into the sitting position.

We have described preferred embodiments of our invention, but it is understood that this disclosure is for the purpose of illustration and that various omissions or changes in shape, proportion and arrangement of parts, as well as the substitution of equivalent elements for those herein shown and described may be made without departing from the spirit and scope of the invention as set forth in the appended claims.

What we claim is:

1. An article of repose for supporting the body of a person, comprising in combination: a support, and a constrained linkage having stationary link-means and a plurality of movable links, said stationary link-means being included in said support, said movable links including a front connecting link, a lower connecting link, guiding means and a seat-back-unit wherein the rear end portion of the seat and the back-rest are pivotally connected and the back-rest has a downward extension projecting beyond the pivotal connection between the seat and the back-rest, the upper end of said front connecting link being pivoted to the front portion of the seat, the lower end of said front connecting link being pivoted to the front end of said lower connecting link, the rear end of said lower connecting link being pivoted to the downward extension of the back-rest, said lower connecting link being pivoted to said support, and said guiding means being connected to said support and being engaged with said seat-back-unit.

2. In an article of repose for supporting the body for a person as claimed in claim 1, biasing means operatively connected with a movable link of said constrained linkage for moving the movable links thereof from a reclined position towards the sitting position.

3. In an article of repose for supporting the body of a person as claimed in claim 1, cooperating stopping means arranged on relatively movable links for limiting an extreme position thereof.

4. In an article of repose for supporting the body of a person as claimed in claim 1, adjustable stopping means arranged on said support for cooperation with a movable link of said constrained linkage so as to limit an extreme position of said movable links, and setting means connected with said adjustable stopping means for setting same in a predetermined position.

5. In an article of repose for supporting the body of a person as claimed in claim 1, a leg-rest swingably mounted on the front end portion of

the seat, and controlling means responsive to movements of a movable link of the constrained linkage, said controlling means being connected to said swingable leg-rest for controlling movements of the latter.

6. In an article of repose for supporting the body of a person as claimed in claim 1, a leg-rest swingably mounted on the front end portion of the seat, a controlling element swingably mounted on said support and connected to a movable link of said constrained linkage, and a controlling link connected to said controlling element and to said leg-rest for controlling the movements of the latter.

7. In an article of repose for supporting the body of a person as claimed in claim 1, a leg-rest swingably mounted on the front end portion of the seat, a controlling element swingably mounted on said support and connected to a movable link of said constrained linkage, said controlling element being in the shape of a bell-crank lever, and a controlling link connected to said controlling element and to said leg-rest for controlling the movements of the latter.

8. An article of repose for supporting the body of a person, comprising in combination: a support, and a constrained linkage having stationary link-means and a plurality of movable links, said stationary link-means being included in said support, said movable links including a front connecting link, a lower connecting link, a guiding link and a seat-back-unit wherein the rear end portion of the seat and the back-rest are pivotally connected and the back-rest has a downward extension projecting beyond the pivotal connection between the seat and the back-rest, the upper end of said front connecting link being pivoted to the front portion of the seat, the lower end of said front connecting link being pivoted to the front end of said lower connecting link, the rear end of said lower connecting link being pivoted to the downward extension of the back-rest, said lower connecting link being pivoted to said support, and said guiding link being swingably mounted on said support and being pivoted to said seat-back-unit.

9. In an article of repose for supporting the body of a person as claimed in claim 8, biasing means operatively connected with a movable link of said constrained linkage for moving the movable links thereof from a reclined position towards the sitting position.

10. In an article of repose for supporting the body of a person as claimed in claim 8, resilient means arranged between said support and a movable link of said constrained linkage for moving the movable links thereof from a reclined position towards the sitting position.

11. In an article of repose for supporting the body of a person as claimed in claim 8, a leg-rest swingably mounted on the front end portion of the seat, a controlling element swingably mounted on said support and rigidly connected with said guiding link, and a controlling link pivoted to said controlling element and to said leg-rest.

12. In an article of repose for supporting the body of a person as claimed in claim 8, said guiding link being pivotally connected with said seat-back-unit in coaxial alignment with the pivotal connection between the seat and the back-rest.

13. In an article of repose for supporting the body of a person as claimed in claim 8, said guiding link being pivotally connected to said seat at a point spaced from the pivotal connection between the seat and the back-rest.

14. In an article of repose for supporting the body of a person as claimed in claim 8, said guiding link being pivotally connected to said back-rest at a point spaced from the pivotal connection between the seat and the back-rest.

15. In an article of repose for supporting the body of a person as claimed in claim 8, said guiding link being pivotally connected to said back-rest at a point spaced from the pivotal connection between the seat and the back-rest, a leg-rest swingably mounted on the front end portion of the seat, a controlling element swingably mounted on said support and rigidly connected with said guiding link, and a controlling link pivoted to said controlling element and to said leg-rest.

16. An article of repose for supporting the body of a person, comprising in combination: a support, and a constrained linkage having stationary link-means and a plurality of movable links, said stationary link-means being included in said support, said movable links including a front connecting link, a lower connecting link, cooperating guiding means and a seat-back-unit wherein the rear end portion of the seat and the back-rest are pivotally connected and the back-rest has a downward extension projecting beyond the pivotal connection between the seat and the back-rest, the upper end of said front connecting link being pivoted to the front portion of the seat, the lower end of said front connecting link being pivoted to the front end of said lower connecting link, the rear end of said lower connecting link being pivoted to the downward extension of the back-rest, said lower connecting link being pivoted to said support, and said cooperating guiding means being slidably engaged with each other and being arranged on said support and said seat-back-unit.

17. In an article of repose for supporting the body of a person as claimed in claim 16, biasing means operatively connected with a movable link of said constrained linkage for moving the movable links thereof from a reclined position towards the sitting position.

18. In an article of repose for supporting the body of a person as claimed in claim 16, resilient means arranged between said support and a movable link of said constrained linkage for moving the movable links thereof from a reclined position towards the sitting position.

19. In an article of repose for supporting the body of a person as claimed in claim 16, a leg-rest swingably mounted on the front end portion of the seat, and controlling means connected to a movable link of said constrained linkage and to said leg-rest for controlling the movements of the latter.

20. In an article of repose for supporting the body of a person as claimed in claim 16, a leg-rest swingably mounted on the front end portion of the seat, a double-armed controlling element swingably mounted on said support, one arm of said controlling element being in pivotal connection with said back-rest, and a controlling link in pivotal connection with the other arm of said controlling element and with said leg-rest.

21. In an article of repose for supporting the body of a person as claimed in claim 16, said cooperating guiding means including a pin and slot connection between said support and said back-rest, said pin being spaced from the pivotal connection between the back-rest and the seat.

22. In an article of repose for supporting the

body of a person as claimed in claim 16, said co-operating guiding means including a pin and slot connection between said support and said seat, said pin being spaced from the pivotal connection between the back-rest and the seat.
